UNITED STATES PATENT OFFICE.

FREDERICK C. SCHERER AND HENRY C. FASHBAUGH, OF COLUMBIANA, OHIO.

INSULATOR.

No. 872,756.

Specification of Letters Patent.

Patented Dec. 3, 1907.

Application filed October 19, 1906. Serial No. 339,650.

To all whom it may concern:

Be it known that we, FREDERICK C. SCHERER and HENRY C. FASHBAUGH, citizens of the United States of America, residing at 5 Columbiana, in the county of Columbiana and State of Ohio, have invented certain new and useful Improvements in Insulators, of which the following is a specification, reference being had therein to the accompanying 10 drawing.

This invention relates to insulators for electric wires, and more particularly to that class of insulators used upon poles supporting telegraph and telephone wires.

15 The primary object of the invention is to provide an insulator to which wires may be readily attached and securely held without the employment of tie wires.

A further object of the invention is to provide 20 an insulator comprising a body portion of vitreous material having a slot to receive and support a wire, and a removable cap of non-conducting material applied to the body portion in such a manner as to confine and 25 secure the wire within the slot of the body portion.

The construction of the improvement will be fully described hereinafter in connection 30 with the accompanying drawing which forms a part of this specification and its novel features will be defined in the appended claims.

In the drawing, Figure 1 is a side elevation of an insulator embodying the invention, Fig. 2 is a vertical sectional view of the 35 same, Fig. 3 is a front elevation of the insulator with parts indicated in dotted lines, and Fig. 4 is a side elevation of a modified construction of the removable cap.

The reference numeral 1 designates the 40 usual wooden pin secured upon a telegraph or telephone pole and threaded at its upper end for the attachment thereto of an insulator comprising a cup-shaped body portion 2, of vitreous material, and a removable cap 3, 45 of non-conducting material, preferably of mica. The cup-shaped body 2 of the insulator is internally threaded to adapt it to be screwed upon the pin 1 and has its upper portion 4 externally screw threaded to engage 50 internal threads 5 formed within the cap 3. The insulator 2 is formed along one side with a transverse recess 6 communicating with a slot 7, formed in the outer surface of the insulator opposite the recess and extending 55 throughout the length of said recess. The wire 8 is applied to the insulator by passing

it through the slot 7 into the recess 6, the latter being of a depth to receive the wire and support it between its side walls. The recesses 6 and slots 7 produce an angular slot 60 in the side of the insulator into which the conducting wire is received, the cap when in position on the insulator having its lower edge projecting below the slot 7 so as to hold the conducting wire within the recess 6. 65

The cap 3 is slightly flared at its lower end to adapt it to fit down over the wire after the latter is in position upon the insulator and the lower edge of said cap bears upon the wire at the opposite ends of the recess, 70 where slight bends may be formed in the wire as shown at 9 in Fig. 3. Thus it will be seen that the wire is firmly secured to the insulator without the employment of a tie wire, thus saving the expense of providing 75 tie wires in addition to the great saving of labor in securing the wires to the insulator incident to the use of such tie wires. Again in case of breakage of a wire between two poles the broken sections of wire will remain 80 connected to the insulators. A further important advantage in the use of our improvement is that the absence of tie wires insures a continuous line conductor which cannot be disturbed by the interruptions and slight 85 breaks and vibrations which are incidental to conductor wires held upon insulators in the ordinary manner. This is a feature of 90 special importance in the erection of telephone lines.

While I prefer to employ glass in the construction of the body 2 of the insulator and molded mica in the manufacture of the removable screw cap, it is obvious that the cap may also be made of glass or any other suitable 95 non-conducting material.

In Fig. 4, I have shown a modified construction of the cap 3, in which the cap is provided with a squared head 3^a instead of the rounded head shown in the other figures, to 100 facilitate its being turned by a suitable wrench or spanner.

We reserve the right to make all such other minor changes in form and construction as may fall within the terms and scope 105 of the following claims.

What we claim and desire to secure by Letters Patent, is:—

In an insulator, a hollow exterior and interior threaded insulator body provided in 110 its outer face with a transversely-extending slot terminating in a vertically-extending

recess, the bottom of said recess being in a plane below the lower wall of the slot, said recess and slot of a length equal to the length of the half of said member, said recess positioned in said member at a point approximately centrally of the inner and outer faces thereof, said slot positioned at a point above the center of said member, and a cap of non-conducting material provided with interior 10 threads, said threads terminating at a point removed from the lower end of the cap thereby providing the inner face at the lower end of the cap with a smooth portion, said cap adapted to be mounted upon said body and

when so positioned the lower end of the cap 15 being in alinement with the bottom of the recess, said recess adapted to receive a conductor wire and said cap adapted to confine said wire in said body when the cap is secured thereto.

20

In testimony whereof we affix our signatures in the presence of two witnesses.

FREDERICK C. SCHERER.
HENRY C. FASHBAUGH.
